Primary Examiner — Selina Sikder(74) *Attorney, Agent, or Firm* — Dolly Wu; General Electric Company(57) **CLAIM**

We claim the ornamental design for an electrical component faceplate, as shown and described.

DESCRIPTION

FIG. 1 is a front perspective view of a electrical component faceplate showing our new design;

FIG. 2 is a front view of the electrical component faceplate design shown in FIG. 1;

FIG. 3 is a top view of the electrical component faceplate design shown in FIG. 1;

FIG. 4 is a bottom view of the electrical component faceplate design shown in FIG. 1;

FIG. 5 is a right view of the electrical component faceplate design shown in FIG. 1;

FIG. 6 is a left view of the electrical component faceplate design shown in FIG. 1; and,

FIG. 7 is a back view of the electrical component faceplate design shown in FIG. 1.

In these drawings, the solid lines illustrate the claimed ornamental design, whereas the broken lines illustrate unclaimed environmental features and form no part of the claimed design.
